UNITED STATES PATENT OFFICE.

ALFRED H. SWARTZ, OF CHICAGO, ILLINOIS, ASSIGNOR TO WILLIAM S. ELLIOTT, OF PITTSBURG, PENNSYLVANIA.

TUBE-CLEANER.

No. 830,808.

Specification of Letters Patent.

Patented Sept. 11, 1906.

Application filed January 31, 1903. Serial No. 141,303.

To all whom it may concern:

Be it known that I, ALFRED H. SWARTZ, of Chicago, Cook county, Illinois, have invented a new and useful Tube-Cleaner, of which the following is a full, clear, and exact description, reference being had to the accompanying drawings, forming part of this specification, in which—

Figure 1 is a sectional side elevation showing a cleaner constructed in accordance with my invention, and Fig. 2 is a detail view of the cleaning-tool proper or head.

My invention relates to that class of tube-cleaners wherein a cleaning tool or tools are rotated by a turbine; and the object of the invention is to provide a simple, cheap, and compact tool of this type which is adapted for small tubes and which will give a rapid and efficient cleaning action upon the scale or foreign matter on the tube.

In the drawings, 2 represents a turbine-casing in which a turbine of any suitable form is mounted, the rotary shaft 3 of this turbine having a universal coupling 4 with a head or plug 5. The cleaning-tool 6 has a wrought iron or steel stem cast into it in casting the tool itself, which stem is screwed into the head 5, and the tool itself consists of a tapering blade of chilled cast-iron having beveled edge portions 8, which are preferably serrated or toothed, as shown. The points of the serrated teeth extend in the opposite direction on one side from that of the other, so that both of them extend in the direction of rotation, and when the turbine is driven the toothed head or blade will swing out under centrifugal force, this being allowed by the universal joint, and while moving around in a generally circular or spiral path will deliver a succession of blows upon the scale to loosen and dislodge it.

The advantages of my invention result from the use of the universal joint in connection with the axial tapering blade or head. The use of this single axial blade with opposite abrading edges enables the device to be used in small tubes, while the angular teeth give a rapid and efficient cutting action.

Variations may be made in the form of the head or blade and the teeth without departing from my invention.

I claim—

1. In a tube-cleaner, a head having flat wings projecting on opposite sides of its longitudinal axis, said wings tapering toward the front end and having oppositely beveled or inclined edges overhanging opposite sides of an axial longitudinal plane, and a screw-stem secured by casting the head about it; substantially as described. 60

2. A tube-cleaner having a head comprising an axial wedge-shaped cutter-body with its opposite edges beveled or inclined in opposite directions to give cutting edges on opposite sides of axial planes, and a stem embedded in the head by casting the head about it; substantially as described. 65

3. A tube-cleaner head comprising a tapered body of hard cast metal, and a screw-stem of softer metal held within a thickened portion of the head; substantially as described.

4. A tube-cleaner head of flat arrow shape having tapered edges and provided with a thickened central portion cast about the stem of a projecting screw; substantially as described. 75

5. A tube-cleaner head of tapered form, having a thickened central portion, the head being of cast metal with the stem of a screw fixed in the thickened cast central portion; substantially as described. 80

6. A tube-cleaner head consisting of a chilled-iron casting of general arrow shape with a thickened central portion cast about the stem of a projecting screw; substantially as described. 85

7. A tube-cleaner head of general arrow shape with tapered serrated edges, beveled in opposite directions with reference to an axial longitudinal plane to give oppositely-projecting cutter edges, the central part of the head being thickened and cast about the stem of a projecting screw to serve as an attaching means; substantially as described. 95

8. In a tube-cleaner, a flat tapered blade having a thickened central portion cast about a projecting screw-stem, and a shaft having universal-joint connection with said stem; substantially as described. 100

9. A tube-cleaner head comprising a body of hard cast metal having tapered or inclined

edges and a threaded portion of softer metal held within a thickened portion of the head and adapted to connect the head to the motor; substantially as described.

5 10. A tube-cleaner head comprising a body of cast metal having cutting edges, and a threaded portion of softer metal held within the rear portion of the head and arranged to

connect it to the driving means; substantially as described.

In testimony whereof I have hereunto set my hand.

ALFRED H. SWARTZ. [L. s.]
